UNITED STATES PATENT OFFICE.

DOUGLAS P. FLETCHER, OF DALLAS, TEXAS.

MOISTENER.

Application filed March 17, 1927. Serial No. 175,979.

This invention relates to new and useful improvements in moisteners.

The principal object of the invention is to provide a moistener including a moistening element and particularly arranged to effectively moisten a small sheet, such as a postage stamp, when the same is passed over the moistening element, and to permit the said small sheet to be easily and readily manipulated during the moistening operation.

A particular object of the invention is to provide a guard of a particular formation arranged to cause a sheet which is passed thereunder to be brought into engagement with the moistening element and to enable the operator to easily handle said sheet and grasp the same.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a side elevation of a moistener constructed in accordance with my invention,

Fig. 2 is a front elevation of the same, a portion of the wick holder being broken away,

Fig. 3 is a partial longitudinal vertical sectional view and showing the wick holder swung outward for the purpose of cleaning,

Fig. 4 is a plan view illustrating the improved guard,

Fig. 5 is a longitudinal vertical sectional view showing another form in which the invention may be carried out and taken on the line 5-5 of Fig. 6,

Fig. 6 is a front elevation of the same, a portion of the tray being broken away,

Fig. 7 is a partial side elevation of the same,

Fig. 8 is a longitudinal vertical sectional view of another form in which the invention may be carried out,

Fig. 9 is a front elevation of the same, and

Fig. 10 is a partial side elevation of the form shown in Fig. 8.

In the drawings the numeral 10 designates a housing which may be of any suitable shape and is preferably constructed of metal lending itself to the production of this par-

ticular device. In the bottom portion of the housing is formed a tray 11 in which the

water or other fluid is placed. The housing has a front wall 12 extending about half way its height and this forms the limit for the liquid level in the tray.

A wick holder 13 is hinged to the upper edge of the wall 12 at 14 and has a rectangular guide 15 forming a part thereof. When swung to its operative position, the holder rests against a pair of lugs 16 bent inwardly from the side walls of the housing. The guide has a pair of vertical slots 17 through which the wick 18 is exposed. The wick extends above the top edge of the guide and hangs down into the tray 11, as is shown in dotted lines in Fig. 1. The wick supplies the liquid at its upper end by capillary attraction.

It will be seen that the wick holder may be swung outward, as is shown in Fig. 3, for cleaning the upper end of the wick when the same becomes coated with glue, or any objectionable substance. A fork member 19 is provided with prongs 20 and these prongs may be engaged with the wick 18 through the slots 17 to feed the wick through the holder when it becomes worn. When the holder 13 is swung inwardly, the shank 21 of the fork member is slid down through a loop 22 on the front wall 12 so that the prongs 20 engage the face of the holder and hold it in position as is illustrated.

A very important feature of the invention is the guard and feed structure which overhangs the wick 18. The top wall 10' of the housing terminates short of the front end so as to permit the wick 18 to project upwardly from the housing. A portion of the said top wall is bent upward at a slight angle to form a feed lip and support 23. The wick extends above this lip but is contiguous to the edge thereof. A guard 24 has a depending side bracket 25, which may be secured to the side of the housing in any suitable manner; either by being made integral therewith, as is shown in Figs. 1, 2 and 3, as well as in 8, 9 and 10, or said bracket may be provided with vertical slots 26 receiving studs 27 carried by the side of the housing and fastened by wing nuts 28 engaging on said studs. Where the guard is rigidly attached to the housing, it is spaced at a fixed distance above the lip; but where it is adjustably mounted, this distance may, of course, be varied.

The guard has its feeding edge 29 cut on a reverse curve receding from the bracket and

gradually reducing the width of said guard. Near its free end the said reverse curve is merged into a concaved formation whereby the guard is provided with a restricted neck

5 30 at this point. The guard is rounded at its free end 31 so as not to injure the hand of the user.

It will be seen that the wick 18 engages the under side of the guard and also that 10 said guard is disposed at an upward inclination in harmony with the lip 23. The neck 30 is quite narrow and exposes a portion of the wick. To moisten a postage stamp, a label, an envelope, or any other 15 article, the same is passed over the lip 23 and between the guard and the wick. Owing to the narrow neck 30, a small sheet may be pushed under the guard with the fingers and grasped on the other side of 20 the guard with the forefinger and thumb. This is particularly useful with postage stamps, which may be quickly and easily handled.

In Figs. 5, 6 and 7, I have shown a removable tray 11' in the housing 10^a which is similar to the housing 10, except for the front wall and wick holder parts. The tray 11' may be filled with liquid and has a holder 32 in its bottom provided with a 25 clamp 33 for frictionally receiving the head 34 of a brush 35. The brush projects through the top of the housing and contacts with the underside of the guard 25. The holder 32 has a fulcrum boss 36 and a 30 rocking finger 37 which is slotted to receive a post 38 fastened to the bottom tray. A wing nut 39 threaded on the upper end of the post bears on the finger 37 and by screwing 35 said nut downward the finger is depressed causing the holder to rock, thus adjusting 40 the brush 35 upwardly.

It is obvious that the invention may be carried out in various ways, particularly as to the moistening element, and in Figs. 8, 9 45 and 10 I have shown another form having a housing 10^b, which has the same top wall 10', but the lip 23' is shortened. The guard 24 overhangs the upper end of an endless belt 40, formed of felt or other suitable 50 material. The lower end of the belt is mounted on a roller 41 journaled in the tray 11 of the housing, while the upper end is mounted on a roller 42 and contacts with the underside of the guard. The roller 42 55 is fastened on a shaft 43 journaled in the sides of the housing and having a thumb wheel 44 on one end, whereby the belt may be adjusted to bring a clean surface under the guard when desired.

Various changes in the size and shape of the different parts, as well as modifications and alterations, may be made within the scope of the appended claims.

What I claim, is:

1. In a moistener, a housing, a moistening element in the housing and a guard carried by the housing contiguous to the upper end of said moistening element, said guard having a transversely reduced portion permitting a small sheet to be grasped on both 65 sides of the guard by the fingers and thumb of the operator.

2. In a moistener, a housing, a moistening element in the housing, and a guard carried by the housing contiguous to the upper end 75 of said moistening element, said guard having a materially reduced neck and being inclined upwardly from its feed side.

3. In a moistener, a housing, an inclined feed lip at the top of the housing, a moistening element contiguous to the lip and extending above said lip, and a guard mounted on the housing and overhanging the moistening element, said guard having a transversely reduced portion permitting a small 85 sheet to be grasped on both sides of the guard by the fingers and thumb of the operator.

4. In a moistener, a housing, an inclined feed lip at the top of the housing, a moistening element contiguous to the lip and extending above said lip, and a guard mounted on the housing and overhanging the moistening element, said guard having a materially reduced neck and being inclined up- 90 wardly from its feed side in harmony with the lip.

5. In a moistening device, a housing, an inclined feed lip at the front end of the housing, a moistening element contiguous 100 to the lip and extending above the said lip, means for adjusting said element, and an inclined guard overhanging the upper end of the moistening element and having a reduced neck.

6. In a moistening device, a housing, an inclined feed lip at the front end of the housing, a moistening element contiguous to the lip and extending above the said lip, means for adjusting said element, an inclined guard overhanging the upper end 110 of the moistening element and having a reduced neck, and a bracket carrying said guard and adjustably mounted on the housing.

In testimony whereof I affix my signature.

DOUGLAS P. FLETCHER.
